UNITED STATES PATENT OFFICE

127,235

DESIGN FOR PAJAMAS

Morris Rubin, Chicago, Ill.

Application February 1, 1940, Serial No. 89,933

Term of patent 3½ years

To all whom it may concern:

Be it known that I, Morris Rubin, a citizen of the United States and a resident of Chicago, in the county of Cook and State of Illinois, have invented a new, original, and ornamental Design for Pajamas, of which the following is a specification, reference being had to the accompanying drawing, forming a part thereof.

In the drawing:

I claim:

The ornamental design for pajamas, as shown.

MORRIS RUBIN.
